UNITED STATES PATENT OFFICE.

EUGENE D. WELLER, OF PHILADELPHIA, PENNSYLVANIA.

VEHICLE.

SPECIFICATION forming part of Letters Patent No. 373,704, dated November 22, 1887.

Application filed January 15, 1887. Serial No. 224,396. (No model.)

To all whom it may concern:

Be it known that I, EUGENE D. WELLER, of the city and county of Philadelphia, in the State of Pennsylvania, have invented certain 5 new and useful Improvements in Vehicles, of which improvements the following is a specification.

My invention has relation to vehicles having longitudinal side springs provided with 10 spring-bars, to which the vehicle-body is secured; and it has for its object to utilize these spring-bars as auxiliary or supplementary springs for supporting a weight or load in excess of that which the side springs are constructed or calculated to carry, and for resisting 15 the downward heavy thrusts of the load incident to traveling over uneven or rough roadways, said spring-bars coming into action at or near the time at which the normal resistance of the side springs is overcome, thereby 20 relieving or protecting them from any injurious strains due to overweight and excessive downward thrusts.

My invention has for its further object to 25 elastically support the ends of the vehicle-body upon the spring-bars, to afford greater ease of riding, and to further protect the side springs as well as the spring-bars from the strains incident to overweight and to downward thrusts when the ends of the spring-bars are in action, to relieve the side springs from 30 such weight and thrust. To accomplish these described results the ends of the spring-bars are free and are extended to project beyond 35 the front and rear axles or bolsters, and these free ends are so constructed and arranged that they are elastic and act as auxiliary or supplementary springs when they impinge against the axles or bolsters.

40 The terms "axles" or "bolsters," as herein employed, are in a measure used synonymous, so as to include axles with or without bolsters. If bolsters are secured to the axles, the ends of the spring-bars strike against the bolsters, 45 and if the latter are not used the ends of said bars impinge against the axles. In no case do said ends meet or strike against the ends of the side springs. Furthermore, both the front and back ends of the spring-bars, or either of 50 said sets of ends, if desired, are connected at suitable points or locations by transverse

springs which at their middle parts or camber are secured to the vehicle-body at a point between the transverse center line and the ends of the body. These transverse springs are so located and attached to the spring-bars and to the vehicle-body that its load or weight does not rest on them, and they do not act to take any weight or resist any downward thrust until the spring-bars are in action, when, if further aid is required for the spring-bars to enable them to resist the overweight and down thrust, the transverse springs then come into action to do so.

My invention accordingly consists, first, of a vehicle having longitudinal side springs, spring-bars secured to the side springs and having free elastic ends which extend to and beyond the rear and front axles, and a body secured to the spring-bars at or near their centers; second, of a vehicle having longitudinal side springs, spring-bars secured to the side springs and having free elastic ends preferably projecting to and beyond the front and rear axles, a body secured to the spring-bars and cross or transverse springs secured at their ends to the elastic extremities of the spring bars and at or near their middle to the bottom of the vehicle-body; and, third, of the combination, construction, and arrangement of parts as hereinafter more particularly described and claimed.

Before describing my improvements in detail I here premise that they are applicable to the usual or other form of side-spring vehicles, and to that form of the same having double sectional perches, the center ends of which are coupled to the center portions of the side springs, a type of which is shown in a pending application filed by me on the 15th day of January, 1887, Serial No. 224,395, and I have therefore illustrated my improvements applied to both said types of vehicles.

Referring to the accompanying drawings Figure 1 represents a perspective of a running-gear for vehicles, showing spring-bars having free elastic ends in accordance with my invention secured to the side springs. Fig. 2, a perspective of central coupling device for double sectional perches, showing the several parts thereof in their respective positions, with a section of one of the perches.

journaled therein; Fig. 3, a vertical longitudinal section of an ordinary construction of vehicle having side springs and spring-bars having free elastic ends in accordance 5 with my invention. Fig. 4 is a top plan of same with body removed and the cross or transverse spring in position on the free elastic ends of the spring-bars; and Fig. 5 is an end elevation, partly sectional, of body, cross-springs, 10 and ends of spring-bars.

A A' are the front and rear axles, and B B' the front and rear bolsters, if used, attached to the axles in any well-understood or suitable manner.

15 C C' are the side springs, suitably attached to the rear and front axles or bolsters, or, as shown in Figs. 1 and 3, so that the ends of the springs are preferably below the top of the axles or bolsters, as and for the purpose here- 20 inafter to be described.

To the camber or middle portion of the side springs, C C', are firmly secured spring-bars G G', respectively. In the drawings these spring-bars are shown secured to the side 25 springs by clips g and g'; but it is obvious that they may otherwise be fastened to the spring-bars, as deemed expedient. These spring-bars have free ends which extend to and beyond the rear and front axles above the same, and 30 these free ends are preferably bowed or curved downwardly toward the axles, as illustrated, so as to bring the ends suitably near to the axles. These spring-bars are preferably made of wood to secure lightness of material com- 35 patible with strength and neatness of finish and design, if desired; but any other suitable material may be employed.

40 J is the vehicle-body, secured in any suitable manner to the spring-bars G G'. In the drawings iron body-supports H and H', clipped to said bars, are shown to effect such secu- 45 ment.

From the foregoing it will be noted that the ends of the side springs are in a plane below 45 that of the top of the axles or bolsters; that the spring-bars preferably follow the line of the side springs or are in the same vertical plane; that the vehicle-body is secured to the spring-bars; that the free elastic ends of the 50 latter curve or bow downwardly away from said body and toward the axles or bolsters, and that the extreme ends of the spring-bars stand over and are located a short distance above the axles or bolsters, said distance being 55 more or less in accordance with the amount of action desired for the free ends of the spring-bars. The side springs, therefore, carry or resist their normal load only, or that which they are intended or constructed to support, to af- 60 ford easy riding, and any undue weight or overload or downward heavy thrust upon the springs due to such extra weight or to the condition of the roadway at once brings the free elastic ends of the spring-bars into resting im- 65 pingement upon the axles or bolsters, causing said ends to take up or resist such overweight and thrust, and as these free elastic ends of the

spring-bars do not strike or bind against the ends of the springs, the movement of the latter is not cramped or restricted when these 70 elastic ends of the side bars are in action. The weight or thrust which induces their action produces no injurious straining of the side springs. More especially so is this the case when the ends of the side springs have a free 75 or sliding connection with the bolsters, as shown in Fig. 1 and as fully described in said pending application.

To prevent any annoying tapping noise of the ends of the spring-bars on the axles or bolsters, elastic pads or cushions h and h' are secured in any desired manner to the under sides of said ends.

As the ends of the spring-bars only come into action after the normal resistance of the 85 side springs is overcome, and in coming into action relieve the side springs, I designate these spring-bars "spring-bar relays," to distinguish them from the usual or other spring-bars which do not have this relay function. 90

To further protect or relieve the side springs of the injurious strains resulting from over-weight and from downward heavy thrust, as well as to relieve or protect the free elastic ends of the spring-bars of corresponding and other 95 strains when in action, I prefer to connect either or both sets of their elastic ends by transverse springs K, which I designate as "cross-spring relays," which are also secured at or near their middle portions to the bottom 100 of the vehicle-body. These cross-springs are located more or less distant, as desired, from the central connection of the side springs and spring-bars, and are preferably of a half-elliptical configuration, as shown. As the 105 body J is secured to the spring-bars and their free ends curve downwardly from the body, the employment of the springs K does not give any support to the body of the vehicle, nor do they come into play until the spring- 110 relays are in action.

My improvements may be applied to single-perch side-spring vehicles, as shown in Figs. 3 and 4, or to double sectional perches, as indicated in Fig. 1. In the latter case I prefer 115 to couple the center ends of the perches to the side springs and connect the rear sections of the perches to the rear axles by crossing truss-rods having tie-rods, as fully shown and de- 120 scribed, and for the purposes set forth in my 125 said pending application--that is to say, D and D' are perches centrally journaled in the coupling devices E, and having their extremities attached by means of clips to the axle and bolster. The central coupling device, E, is held rigidly to the foundation-spring C or C' by the spring-clips F. This central coupling 130 device, E, made of any suitable metal, is pref- 135 erably constructed in two parts, e and e', which are the box and main plates, having flanged sloping sides e² and ears e³, provided with holes therein for the insertion of the clip-shanks e⁴, secured in place by means of nuts. The box-plate e has a leg, e⁵, dovetailed at the bottom

- of the main plate e' . The two plates are fitted solidly together by passing the shanks of the clips e^4 on each side of the coupling device through the openings in the ears e^3 and fitting nuts thereon. The internal extremities of the clips are fitted to place by passing a set-screw, e^6 , upward through the bottom of the main plate e' and through openings in the clips and box-plate e .
- 10 In the box-plate e , on each side of its leg, journal-boxes f and f' are provided for the reception of the journals d and d' of the perches D and D' , held therein by means of metallic washers d^2 , having pins secured in one side of each washer and fitting into slots formed in the side walls of the journal-boxes of the plate e . This metallic washer d^2 and receiving box-plate e are made of anti-friction metal. A curved face is preferably given to the washer, in order that it may conform to the contour of the journals of the perches, having a flanged bottom rim curved transversely to that of its face, as shown in Fig. 2, for firmly supporting an elastic presser, e^7 , inserted between the clip e and the metallic washer d^2 .
- 15 The several parts being secured to place in the manner above described, the journals d and d' of the perches D and D' will be snugly held in position in their journal-boxes f and f' without rattle or squeak, while the perches at the same time will be free to move synchronously with the vertical action of the foundation-springs C and C' , either upward or downward; and, furthermore, in case the two axles should cant in opposite directions in the movement of the vehicle, which they are likely to do, the journals of the perches will cant similarly without strain, as the anti-friction metallic washer d^2 and elastic presser e^7 of the coupling device easily yield, compensating for any and all such movements of the vehicle.
- 20 In the space between the journal-boxes f and f' of the box-plate e , and along the leg e^8 thereof, is provided a series of vertical holes which extend through the box and back plates, and through which holes the shanks of the clips encircling the foundation-springs C and C' are inserted and held firmly thereto by means of nuts, so that, when desired, the central coupling device may be mounted higher or lower, as may be desired, by simply removing the nuts from the clip-shanks and inserting them in an upper or lower set of holes in the central coupling device.
- 25 To the rear axle, A , beyond where the respective side springs are suitably supported, are attached by means of clips truss-rods I and I' . The truss-rod I , for instance, as shown in Fig. 1, is secured to the axle A' by means of a clip, i , and thence reaches therefrom in a practically straight line or inclining slightly downward to the perch D' , where, by means of bolts i^2 , passing through the T-shaped strut i^3 , the truss-rod I is secured to the perch D' , thence sloping in an upward direction to the opposite perch, D^2 , at a point just below where the shank d^3 of this perch D^2 rises, at which point it is suitably clipped thereto. The respective truss-rods at their crossing receive a bolt and nut, i^4 , for holding them tightly together. The other truss-rod, i' , in a similar manner is secured to the axle A' by means of a clip, i , and thence reaches therefrom to the perch D^2 , where it is fastened by means of bolts passing through the T-shaped strut i^3 to the perch, thence inclining upward to the extremity of the perch D^2 , where it is fastened to the same by means of a clip, i^4 .
- 30 The respective truss-rods are provided with tie-rods i^5 , for furnishing additional strength to them, at a point near where the struts are secured to the undersides of the perches, whereby through this arrangement of the truss-rods to the perches and axle, respectively, the inner extremities of the perches are upon them, as shown and described.
- 35 As in some instances one or both of the cross-spring relays may be dispensed with, I do not wish to be understood as limiting my invention to the construction and arrangement herein illustrated and set forth, and the spring-bar relays and cross-spring relays may be made and located as desired in practice for best satisfactorily accomplishing the end and purpose desired, without, however, departing from the spirit of the invention.
- 40 What I claim is—
1. In a vehicle, the combination of front and rear axles, side springs connected to said axles, a body secured to spring-bars, which in turn are secured to the sidesprings, and said spring-bars having free elastic ends extending to and beyond the axles above the same for impingement against the axles, to act as relay or auxiliary springs when the normal resistance of the side springs is overcome, substantially as set forth.
  2. In a side-spring vehicle, spring-bars having free elastic ends, which have a resting impingement upon the front and rear axles or bolsters, to serve as auxiliary springs when the normal resistance of the side springs is overcome, substantially as set forth.
  3. In a side-spring vehicle, spring-bars having free elastic ends having on their extremities rubber or elastic pads h h' , for resting impingement against the front and rear axles or bolsters, to serve as relay or auxiliary springs when the normal resistance of the side springs is overcome, substantially as set forth.
  4. In a side-spring vehicle, spring-bars having free elastic ends for resting impingement upon the front and rear axles when the normal resistance of the side springs is overcome, a body affixed to the spring-bars, cross-springs secured at their cambers or middle portions to the bottom of the body and at their ends to the free elastic ends of the spring-bars, and said cross-springs coming into action when the free elastic ends of the spring-bars are in service as auxiliary springs, substantially as set forth.
  5. In a side-spring vehicle, spring-bars hav-

ing free elastic ends, cross-springs connecting said ends, a vehicle-body secured to said spring-bars and cross-springs, and said spring-bar free elastic ends and the cross-springs being arranged to come into action successively when the normal resistance of the side springs is overcome, substantially as set forth.

6. In a side-spring vehicle, spring-bars having free elastic ends, cross-springs connected at their extremities to the free ends of the spring-bars, and a vehicle body secured to the middle portions of the spring-bars and to corresponding portions of the cross springs, substantially as set forth.

15 7. In a vehicle, the combination of front and rear axles, side springs connecting said axles or their bolsters, sectional perches having their center ends coupled to the side springs, spring-bars secured to the side springs and having free elastic ends for resting impingement against said axles or bolsters when the normal resistance of the side springs is overcome, and a vehicle-body secured to the spring-bars, substantially as set forth.

25 8. In a vehicle, the combination of front and rear axles, side springs connecting said axles or their bolsters, sectional perches, vertically-

adjustable couplings for securing the center ends of the sectional perches to the side springs, spring-bars secured to the side springs and having free elastic ends for resting impingement against said axles or bolsters when the normal resistance of the side springs is overcome, and a vehicle-body secured to the spring-bars, substantially as set forth.

35 9. In a vehicle, the combination of front and rear axles, side springs connecting said axles or their bolsters, sectional perches having their center ends coupled to the side springs, crossing strut-rods having tie-rods connecting the rear axle to the rear perch-sections, spring-bars secured to the side springs and having free elastic ends for resting impingement against said axles or bolsters when the normal resistance of the side springs is overcome, and a vehicle-body secured to the spring-bars, substantially as set forth.

40 In witness whereof I have hereunto set my hand in the presence of two subscribing witnesses.

E. D. WELLER.
